UNITED STATES PATENT OFFICE

164,488

STORE SERVICE TRUCK

Sylvan N. Goldman, Oklahoma City, Okla.

Application May 16, 1950, Serial No. 9,980

Term of patent 14 years

(Cl. D14—3)

To all whom it may concern:

Be it known that I, Sylvan N. Goldman, a citizen of the United States, residing at Oklahoma City, in the county of Oklahoma and State of Oklahoma, have invented a new, original, and ornamental Design for a Store Service Truck, of which the following is a specification, reference being had to the accompanying drawing, forming a part hereof.

The figure is a perspective view of the invention.

I claim:

The ornamental design for a store service truck, as shown.

SYLVAN N. GOLDMAN.
